UNITED STATES PATENT OFFICE.

AXEL W. NILSSON, OF NEW YORK, N. Y.

DESIGN FOR TILING FOR FLOOR AND WALL COVERINGS.

SPECIFICATION forming part of Design No. 36,906, dated May 3, 1904.

Application filed March 9, 1904. Serial No. 197,372. Term of patent 14 years.

To all whom it may concern:

Be it known that I, AXEL W. NILSSON, a citizen of the United States, residing in the city, county, and State of New York, have invented 5 a new, original, and ornamental Design for Tiling for Floor and Wall Coverings, shown in the accompanying drawing.

The figure of the drawing shows the design of the floor or wall covering in plan.

What I claim is—

The ornamental design for tiling for floor and wall coverings, as herein shown.

AXEL W. NILSSON.
